UNITED STATES PATENT OFFICE.

ARTHUR G. SARGENT, OF TILTON, AND LOUIS B. MARTIN, OF LACONIA,
NEW HAMPSHIRE, ASSIGNEES, BY DIRECT AND MESNE ASSIGNMENTS,
TO LEON J. MERCHANT, OF LACONIA, NEW HAMPSHIRE.

PRESS FOR PRINTING MENUS, &c.

SPECIFICATION forming part of Letters Patent No. 623,930, dated April 25, 1899.

Application filed June 6, 1898. Serial No. 682,637. (No model.)

To all whom it may concern:

Be it known that we, ARTHUR G. SARGENT, of Tilton, and LOUIS B. MARTIN, of Laconia, in the county of Belknap and State of New Hampshire, have invented certain new and useful Improvements in Presses for Printing Menus, of which the following is a description sufficiently full, clear, and exact to enable those skilled in the art to which it applies or with which it is most nearly connected to make and use the same.

This invention has relation to printing-presses generally, and particularly to hand printing-presses adapted to print menus or bills of fare and similar things.

It is the object of the invention to provide a printing-press of the character described which shall be efficient for the purpose for which it is intended and which shall be capable of being used by an ordinarily intelligent person and not necessarily by one skilled in the art of printing.

The invention contemplates the use of type-bars or slugs cast, it may be, as is done by so-called "linotype-machine," so as to obviate type-setting, and an inking-pad similar in function to inking-pads employed with commonly-used hand-stamps.

To these ends and with this understanding the invention consists of an organized printing-press employing in its construction a suitable frame, a sliding or movable bed on the frame, a slug-holder adapted to be secured on the bed, a depressible ink-pad and a depressible press-platen, and a lever or other suitable means for sliding the bed to and fro to depress the ink-pad to ink the type and the platen to make the impression on the card or sheet to be printed, as is hereinafter particularly specified.

The invention also consists of improvements embodied in groups of parts in the said organized printing-press, as will appear from the subjoined description and claims.

Reference is to be had to the annexed drawings, and to the letters marked thereon, forming a part of this specification, the same letters designating the same parts or features, as the case may be, wherever they occur.

Of the drawings, Figure 1 is a plan view of 50 our improved printing-press complete. Fig. 2 is a side elevation thereof, the bed being shown as moved under the ink-pad ready to have the latter depressed. Fig. 3 is a longitudinal vertical sectional view of the machine. 55 Fig. 4 is a front end view of the same.

The frame of the machine comprises a base-plate *a*, to which are secured uprights *b b'*, which uprights, with the standards *c*, support the plate *d*, the latter in turn support- 60 ing beneath it the platen *e* and the ink-pad *f*. The ink-pad and platen are normally held in raised position by means of springs *g* operating between the heads of bolts connected with the said pad and platen and the plate *d*, 65 so that the ink-pad and platen may be depressed to a limited extent by pressure applied thereon and be raised, as before indicated, by means of springs. A shaft *h* is secured in the upper ends of the uprights *b*, and 70 a rock-rod *i* is journaled in suitable bearings in the upper ends of the uprights *b'*.

j designates an eccentric to the shaft *h*, and to a strap *k*, surrounding the said eccentric, there is attached an operating-lever *l*. Arranged to turn on the shaft *h* is a collar *m*, and from a part connected therewith there extends downward a crank *n*, between the lower end of which and the end of a crank *o* on the rock-rod *i* there is a pitman or link *p*. Connected 80 with the collar *m* is a disk *q*, provided in its periphery with a notch *r*, adapted to receive a dog *s*, connected with the strap *k*, surround- 85 ing the eccentric on the shaft *h*. As the handle *l* is operated to and fro the dog *s* will engage the notch *r* in the disk *q* and turn said disk to a limited extent or until the eccentric carries the dog out of engagement with the said notch, and so move the collar *m* and parts connected therewith so long as it is in engage- 90 ment with the notch of the disk *q*, and when the collar *m* is moved, as aforesaid, by operating the lever the cranks *n o* will be operated, operating the rock-rod *i*, which is connected through the medium of links *t u* with the bed 95 *v* of the machine, and so move said bed to and fro on the base *a*, it being guided in suitable tracks or ways. (Best shown perhaps in

Fig. 4.) This movement of the bed to and fro will carry it first under the inking-pad, so that it may be inked, and then back under the platen *e*, so that the latter may be pressed down thereon and print the ink-type upon the paper or card placed between the type and the lower surface of the bed.

Connected with the strap surrounding the eccentric *j* is a curved finger *w* in front and a cam *x* to the rear or on the bottom. When the operating-lever is moved over forward, the finger *w* will be brought to bear upon the free end of a lever *y*, adapted to bear on an adjusting-screw *z*, connected with a boss on the ink-pad, and so depress the said ink-pad upon the type carried by the bed, and when the operating-lever is moved back in the opposite direction the cam *x* will act upon a short lever *a'*, resting upon an adjusting-screw *c'*, tapped into a boss extending upward from the platen *e*, and so depress the said platen upon the paper or card between the lower surface thereof and the type carried by the bed.

The dog *s* is engaged with the disk *y* on the collar just long enough in the movement of the lever to move the bed from under the platen to position under the ink-pad and back again. After the bed *v* is moved to each of the limits mentioned the dog is disengaged from the disk, and the further movement of the lever or handle *l* operates through the devices before described to depress either the ink-pad or platen, as hereinbefore explained, and the construction and timing of the means for moving the type-bed are such that the said type-bed will reach the limits of its reciprocating movements before either the ink-pad or platen is depressed.

d' designates a type-carrier adapted to receive slugs or type-bars *e'* thereon and to have them locked in position by the locking-screw *f'* operating against the sides thereof, as best shown in Fig. 3. The said type-carrier is arranged to be moved into place on the bed *v* and to be held in place thereon by any proper means, the object of employing a type-carrier being to provide means whereby the type-holder may be drawn out, so that the matter composing the bill of fare may be altered by changing the slugs or type-bars and so as to allow the said matter to be readily locked in the type-carrier.

Connected with the sides of the platen *e* are strips *g'* of metal extending below the surface of the lower face of the platen, and just inside the strips *g'* are narrow strips of steel or similar metal *h*, forming springs, the said strips and springs together constituting guides for the card or paper, which may be moved into place beneath the platen and held there while being printed—that is, while the impression is being made upon the paper, as before described.

The ink-pad may be supposed to be of such a nature as is commonly used with rubber stamps, and it may have ink applied thereto

by any suitable means when the type-bed is moved forward under the platen.

The machine as a whole constitutes a very compact and efficient contrivance whereby hotel men and restaurant keepers and others not having ready access to a printing-office or not having a sufficiently profitable business to warrant the regular printing of a bill of fare daily may print their own menu or other similar matter.

While the machine is designed as a menu-printer, it is obvious that at the same time it is adapted for printing other things.

While we have shown what we at present consider the best form of devices for embodying our invention in a printing-press, we would have it understood that changes may be made in the form and arrangement of some of the parts constituting the invention without departing from the nature and spirit of our invention.

Having thus explained the nature of the invention and described a way of constructing and using the same, though without attempting to set forth all the forms in which it may be made or all of the modes of its use, it is declared that what is claimed is—

1. In a printing-press the combination of a reciprocating type-bed, an inking-pad arranged above the path of the type-bed, springs for lifting the inking-pad away from the type, a platen also arranged above the path of the type-bed, springs for lifting said platen away from the type-bed, and means for successively depressing the inking-pad and the platen.

2. In a printing-press the combination, with the reciprocating type-bed, the inking-pad and the platen arranged above the type-bed, springs for holding the pad and the platen away from the type-bed, the rock-shaft, a pair of cams thereon for successively depressing the pad and the platen against the type, and means actuated by said rock-shaft for reciprocating said type-bed, substantially as described.

3. In a printing-press the combination with the reciprocating type-bed of the inking-pad and the platen arranged above the path of the type-bed, springs for lifting and holding the platen and pad away from the type, the rock-shaft provided with means for successively depressing the pad and the platen, said rock-shaft having a link connection with the pivoted lever for reciprocating the type-bed.

In testimony whereof we have signed our names to this specification, in the presence of two subscribing witnesses, this 28th day of May, A. D. 1898.

ARTHUR G. SARGENT.
LOUIS B. MARTIN.
